(57) **CLAIM**

The ornamental design for a floor stand for a photobiomodulation therapy device, as shown and described.

DESCRIPTION

FIG. 1 is a front, first side, and top perspective view of a floor stand for a photobiomodulation therapy device embodying the new design;

FIG. 2 is a back, second side, and top perspective view thereof;

FIG. 3 is a front view thereof;

FIG. 4 is a back view thereof;

FIG. 5 is a first side view thereof;

FIG. 6 is a second side view thereof;

FIG. 7 is a top view thereof;

FIG. 8 is a bottom view thereof;

FIG. 9 is a front, first side, and top perspective view thereof including a photobiomodulation therapy device coupled to the floor stand for a photobiomodulation therapy device; and,

FIG. 10 is a back, second side, and top perspective view thereof.

The broken lines in FIGS. 1-8 depict portions of the floor stand for a photobiomodulation therapy device that form no part of the claimed design; and the broken lines showing the photobiomodulation therapy device in FIGS. 9 and 10 represent environmental structure and form no part of the claimed design.
